Pierre Desbaules
By B. Singer, Atty.

UNITED STATES PATENT OFFICE

CHARLES CHAPUIS AND PIERRE DESSAULES, OF CHALONS-S-SAONE, FRANCE

LEVER SYSTEM

Application filed June 1, 1928, Serial No. 282,184, and in France June 8, 1927.

This invention relates to improvements in lever systems for receiving a force and transmitting it in a line parallel with that in which it was applied.

5 According to the invention two principal levers are employed a first lever to which the force is applied, a second lever pivoted to the first and to a moving point and auxiliary arms or levers to guide and carry the point of suspension of the second lever.

10 The invention will be described with reference to the accompanying drawings.

Fig. 1 is a plan showing the arms in the central position.

15 Fig. 2 is a similar view with the arms extended.

Fig. 3 is a sectional elevation on line 3—3 of Fig. 1.

According to the preferred form of the invention two levers α^1 , α^2 are connected together by a pin b . The lever α^1 is pivoted about a stationary pin c . The arm α^2 is pivoted about a movable stud D and carries at one end a point of attachment e .

20 One end of the lever α^1 is connected by a pin f^1 in a slot f to an arm g which is pivoted at h on to a link i oscillating about a stationary point j the arm g being provided at its other end with a projection k which works 25 in a longitudinal slot l in the framework. This same end of the arm g is also provided with a slotted heart-shaped cam m engaged by a pin n carried by a further lever o pivoted about a stationary pin p which arm carries 30 the aforesaid point of oscillation D of the arm α^2 .

To assist the working of the pin n in the cam m an auxiliary lever q is pivoted about n and provided with a small pin r which travels over a portion of the outer surface s of the cam m to ease the pin over the dead center position. This pin r may be replaced by a runner bearing on the cam surface.

35 In operation, if the lever α^1 is given an angular displacement the pin D above which the arm α^2 pivots will move from d to d^1 through an angle B causing the point e to move to e^1 . (Fig. 2.) During this movement the pin f^1 on the arm g has been dis-

placed to a greater extent in the slot f as the pin n has traveled to one end of the slot in the cam m .

This arrangement of levers is applicable for transmitting a reciprocating motion acting on a straight line with either an increased or a decreased displacement, according to the length of the arms α^1 and α^2 .

45 What we claim as our invention and desire to protect by Letters Patent is:—

A lever system comprising a frame, an operating arm pivotally connected thereto, a second arm pivotally connected to the operating arm, a stud on the other end of said second arm entering a slot in said frame and a link also connecting the second arm to the frame, a cam surface mounted on the second arm, a second link and a pin on said link engaging the cam surface, a second pin carried by said link, a further lever pivoted upon such pin, a second pin on said lever by which it is connected to the first mentioned lever, this further lever being that from which power is delivered, and a guide link pivoted to the frame and to the pin travelling over the cam to facilitate the working of this latter.

50 In witness whereof we affix our signatures.

CHARLES CHAPUIS.

PIERRE DESSAULES.
